BRASSIÈRE

Gabrielle M. P. Yerkes, Hartsdale, N. Y., assignor
to G. M. Poix, Inc., New York, N. Y., a corpora-
tion of New York

Application June 27, 1933, Serial No. 677,772

2 Claims. (Cl. 2—42)

The object of my invention is to provide a brassière which may be worn effectively and comfortably with backless garments, such as evening dresses, swimming suits, or any other garment in connection with which such a brassière could be worn.

5 My invention comprises a brassière having fulled breast portions terminating in tapered end portions; straps being provided for passing over the shoulders of the wearer, and straps being provided which depend from the brassière and have leg encircling loops, said depending straps being adapted to be crossed at the back of the wearer below the waistline, the encircling loops for the 10 right and left legs respectively, being continuations of the left and right depending straps respectively.

A practical embodiment of my invention is represented in the accompanying drawing, in which 15 Fig. 1 represents a front view of the brassière as in use, and

Fig. 2 represents a back view of the brassière as in use.

The brassière comprises two fulled breast portions 20 1 and 2, composed preferably of elastic woven or knitted material, said breast portions terminating in tapered end portions 3 and 4, preferably made of the same material as the breast portions.

Shoulder straps 5 and 6, preferably of elastic 25 material, are connected at their front ends to the upper edges of the fulled breast portions 1 and 2 of the brassière, and at their back ends to the tips of the tapered end portions 3 and 4 of the brassière.

30 Depending straps 7 and 8 of elastic material are secured at their upper ends to the tips of the tapered end portions 3 and 4 of the brassière, which elastic straps are provided at their lower ends with elastic leg encircling loops 9 and 10. 35 These depending straps 7 and 8, when the brassière is in use, are crossed at the back of the wearer below the waistline, the right and left leg encircling loops being carried by the straps depending from the left and right tapered end portions 40 respectively of the brassière.

The brassière may be put on by first placing the shoulder straps over the shoulders of the wearer and positioning the breast portions of the brassière. The depending straps may then be 45 crossed at the back of the wearer and the right leg inserted through the loop of the left strap and the left leg through the loop of the right strap.

50 These shoulder straps 5 and 6 of the brassière and the crossed depending straps 7 and 8 with

their leg encircling loops 9 and 10 coact to hold the breast and tapered end portions of the brassière snugly on the wearer and yet leaving the back of the wearer above the waistline free of straps, thus rendering the brassière particularly 60 applicable for use with backless garments of any kind.

It is evident that various changes may be resorted to in the construction, form and arrangement of the several parts without departing from 65 the spirit and scope of my invention, and hence I do not intend to be limited to the particular embodiment herein shown and described, but what I claim is:

1. A brassière including fulled breast portions 70 terminating in tapered end portions having their tips spaced apart and unconnected at the back of the wearer, shoulder straps connected to the breast portions and the tips of the tapered end portions respectively and depending elastic 75 crossed straps secured at their upper ends to the tips of the tapered end portions and being provided at their lower ends with elastic uninterrupted leg encircling loops.

2. A brassière including fulled breast portions 80 terminating in tapered end portions having their tips spaced apart and unconnected at the back of the wearer, shoulder straps connected to the breast portions and the tips of the tapered end portions respectively and depending elastic 85 crossed straps secured at their upper ends to the tips of the tapered end portions and being provided at their lower ends with elastic uninterrupted leg encircling loops, said depending straps being crossed at the back, below the waistline. 90
